UNITED STATES PATENT OFFICE.

FREDERICK W. TUERK, JR., OF BERLIN, CANADA.

IMPROVEMENT IN WATER-WHEELS.

Specification forming part of Letters Patent No. 154,532, dated August 25, 1874; application filed July 18, 1874.

To all whom it may concern:

Be it known that I, FREDERICK W. TUERK, Jr., of Berlin, in the county of Waterloo, Province of Ontario, Dominion of Canada, have invented a new and useful Improvement in Water-Wheels, of which the following is a specification:

Figure 1, Sheet 1, is a horizontal section of my improved wheel, taken through the line *y y*, Fig. 3. Fig. 2, Sheet 1, is a horizontal section of the same, taken through the line *z z*, Fig. 3. Fig. 3, Sheet 2, is a side view of the same, partly in vertical section through the line *x x*, Figs. 1 and 2. Fig. 4, Sheet 2, is a bottom view of the same. Fig. 5, Sheet 2, is a detail view, showing the manner in which the buckets are hinged to the rim of the wheel. Fig. 6, Sheet 2, is a view showing a modification of the same.

Similar letters of reference indicate corresponding parts.

My invention has for its object to furnish an improved water-wheel which may be run with a very low head of water, and which shall be free from back-pressure and waste, and will thus utilize almost the entire force of the water. The invention consists in the combination of curved and pivoted buckets with the wheel, having wedge-shaped recesses in its rim; in the wedge-shaped recesses formed in the rim of the wheel beneath the upper part of the buckets, in connection with the curved slots in the partition-plate, provided with the two sets of openings and the ring-flange, in combination with the parts of the case and with the wheel; and in the combination of the sliding plates or gates, the cross-arm, the curved and toothed cross-head, the gear-wheel, and the shaft and hand-wheel with the case, for regulating the size of the discharge-orifices of the case, as hereinafter fully described.

A is the lower part of the case, which is attached to and supported by a suitable framework, so that the outflowing water may pass off without obstruction. *B* is the wheel, the hub of which is attached to the shaft *C*, from which motion is communicated to the machinery to be driven. *D* is the upper part of the case, into which the water is admitted through the chute *E*, which enters a hole in the top of said

case. The flanged lower edge of the case *D* is bolted to the flanged upper edge of the case *A*, a partition, *F*, being interposed between them, and secured by the bolts that secure the parts of the case to each other. In the opposite parts of the partition *F*, and directly over the outer edge of the rim of the wheel *B*, are formed two narrow slots, *f¹*, which are curved upon the arc of the said rim. In the partition *F*, a little in the rear of the slots *f¹*, and in the forward part of the side enlargements of the parts *A* *D* of the case, are formed large openings, *f²*, through which the main body of the water passes to drive the wheel. To the partition *F*, between the openings *f¹* *f²*, is attached a ring-flange, *f³*, as shown in Figs. 1 and 3. *b¹* are the buckets, which are curved in the form of the rim of the wheel *B*, so as to fit into shallow recesses in the outer surface of said rim, and leave their outer surfaces flush with the outer surface of said rim. Upon the concaved side of the inner edges of the buckets *b¹* are formed cylindrical ribs, which fit into similarly-shaped recesses formed in the rim of the wheel *B* at the forward edges of the recesses that receive the buckets *b¹*, and which are so formed that the buckets *b¹* may be shut down upon said rim or opened out at an angle with said rim, as shown in Fig. 2. The buckets *b¹*, when opened out, are supported against the pressure of the water by resting against the front and rear sides of the recesses in which their cylindrical ribs rest, the rim of the wheel *B* thus supporting the entire strain. The buckets *b¹* are kept in place by small cap-plates attached to the upper and lower edges of the rim of the wheel *B*, so as to cover the ends of the cylindrical ribs of said buckets. To these cap-plates are attached short pivots, which enter holes in the ends of the cylindrical ribs of the buckets, to diminish the friction as the said buckets move out and in. In the rim of the wheel *B*, beneath the upper parts of the buckets *b¹*, are formed wedge-shaped recesses *b²*, as shown in Figs. 2 and 3. This form adapts them for the admission of water beneath the free ends of the buckets, as the latter in the revolution of wheel *B* come successively opposite the inlet-opening, thus causing the buckets to be instantly opened outward to receive the full impact of the water.

Upon the inner surface of the middle parts of the enlargements of the case A D are formed flanges G, which project inward and forward, so that their inner or forward ends may rest against the rim of the wheel B, and serve as chutes to guide the water to the buckets. The lower end of the shaft C revolves upon a lignum-vitæ step, H, which is fitted into a metallic cup, I, which rests in a socket in the center of the spider J, the arms of which are connected with the bottom of the case A. K is a set-screw, which passes in through the center of the spider J, and the end of which rests against the center of the bottom of the step-cup I, so that by turning the said screw the shaft C and wheel B may be raised and lowered to adjust the wheel B, as required. In the bottom of the case A, just in the rear of the flanges or chutes G, are formed the discharge-openings, so that the water must make a half-circuit before it can escape. The discharge-openings are covered with sliding plates or gates L, which slide in ways attached to the bottom of the case A, and to them are attached the ends of the cross-bar M, in the center of which is formed a hole to receive the lower end of the hub of the spider J, so that the two plates or gates may always move together. Upon one end of the cross-bar M is formed a cross-head, N, which is curved upon the arc of a circle, and has teeth formed upon its convex or outer side, into which mesh the teeth of a small gear-wheel, O, attached to the vertical rod or shaft P, which works in bearings attached to the case A D, and to its upper end is attached a hand-wheel, Q, so that the gates L can be readily adjusted to regulate the escape of the water, as may be desired.

With this construction, when the water is admitted through the chute E, it flows through the openings f¹, being guided by the ring-flange

f³, enters the wedge-shaped recesses b², and forces the buckets b¹ outward, as indicated by the arrows 1, so that the water that enters through the openings f² may strike against them, as indicated by arrows 2, and drive the wheel forward in the direction of the unmarked arrows. As each bucket enters the enlargement of the case A the water flows past them and strikes against the rear sides of the flanges or chutes G, and is thrown back against the forward side of the buckets, closing them before they can strike against the said flanges or chutes.

Having thus described my invention, what I claim as new, and desire to secure by Letters Patent, is—

1. The combination of the pivoted buckets b¹ with the wheel B, having wedge-shaped recesses b² to receive them, as shown and described, for the purpose specified.
2. The wedge-shaped recesses b², formed in the rim of the wheel B, beneath the upper part of the buckets b¹, in connection with the curved slots f¹ in the partition-plate F, substantially as herein shown and described.
3. The partition-plate F, provided with the openings f¹ and f², and the ring-flange f³, in combination with the parts A D of the case, and with the wheel B b¹, substantially as herein shown and described.
4. The combination of the sliding plates or gates L, the cross-arm M, the curved and toothed cross-head N, the gear-wheel O, and the shaft and hand-wheel P Q with the case A D, for regulating the size of the discharge- orifices of said case, substantially as herein shown and described.

FREDERICK W. TUERK, JR.
